(57) **CLAIM**

The ornamental design for a washer, as shown and described.

DESCRIPTION

FIG. 1 is a top front side perspective view of a washer showing the design of the present disclosure in its combined configuration;

FIG. 2 is a bottom rear side perspective view of the washer of FIG. 1;

FIG. 3 is a front elevation view of the washer of FIG. 1;

FIG. 4 is a rear elevation view of the washer of FIG. 1;

FIG. 5 is a left elevation view of the washer of FIG. 1;

FIG. 6 is a right elevation view of the washer of FIG. 1;

FIG. 7 is a top plan view of the washer of FIG. 1; and,

FIG. 8 is a bottom plan view of the washer of FIG. 1.
